UNITED STATES PATENT OFFICE.

JAMES M. DODGE, OF PHILADELPHIA, PENNSYLVANIA, ASSIGNOR TO THE
LINK-BELT ENGINEERING COMPANY, OF SAME PLACE.

CONVEYER.

SPECIFICATION forming part of Letters Patent No. 499,525, dated June 13, 1893.

Application filed January 23, 1893. Serial No. 459,420. (No model.)

To all whom it may concern:

Be it known that I, JAMES M. DODGE, a citizen of the United States, and a resident of Philadelphia, Pennsylvania, have invented 5 certain Improvements in Conveyers, of which the following is a specification.

The object of my invention is to construct a conveyer of jointed rods in such a manner that the flights will have free movement, and 10 the joints will allow the conveyer to readily turn curves or pass around a drive wheel or carrier. This object I attain in the following manner, reference being had to the accompanying drawings, in which—

15 Figure 1, is a longitudinal view partly in section illustrating my improved conveyer. Fig. 2, is a sectional view on the line 1—2, Fig. 1. Fig. 3, is a perspective view of one section of the conveyer showing the parts detached, some of said parts being in section. Figs. 4, 5, 6, 7, 8, and 9, are views illustrating modifications of my invention.

20 Are a series of rods made in the present instance in the form of bolts, having their ends a, a' so shaped that when they are applied to their sockets, they will not turn, and I preferably form a head a^2 on one end, and thread the opposite end a^3 beyond the portion a' to which is fitted a nut B, but the parts may be 25 riveted, or other means of fastening may be employed without departing from my invention. The head a^2 , as well as the portion a , is adapted to an opening d in a shell D, the opening corresponding to the shape of the 30 portion a and head a^2 , so as to prevent the rod A turning in the shell. In some instances only one part may be shaped to correspond with the opening d . Secured to the shell is a cap D'. The inner portions of the 35 shell and cap are shaped to form a socket for the ball E, an opening e being formed in the ball to receive the shaped portion a' of the bolt, and the nut B. The opening d' in the cap D' is flared so as to allow for the free 40 movement of the bolt to which is attached the ball E. The cap, as shown in Figs. 1 and 2, as well as in Fig. 3, has a flange f' corresponding 45 to a flange f on the shell D, and clamp bolts F provided with suitable nuts, pass

through the flanges and secure the cap to the shell. In some instances, the flange f or the flange f' , may project sufficiently to form a flight shown in Fig. 4, and in dotted lines in Fig. 1, or a separable flight G may be clamped between the cap and shell as shown in full lines in Fig. 1, and this flight may be made of sheet metal if desired. The flight may be circular as shown in Fig. 2, or square as shown by dotted lines in said figure, or may be shaped as shown in Fig. 8, depending altogether upon the use for which the conveyer is intended, and the shape of the trough or conveyer casing.

In Fig. 4, I have shown the cap having a screw-threaded periphery adapted to the threaded casing, and when necessary a set screw may be used to lock the cap to the casing. In this figure, I have also shown a steel bushing d^2 for the cap, against which the ball bears.

In some instances, the head of the rod A may be spherical as shown in Fig. 4, and the nut applied to the opposite end of the rod, and adapted to a socket in the shell D preventing the nut turning on the rod. It will also be observed that when a separable ball is used as in Fig. 1, the nut is prevented from turning on the rod, as the portion a' as well as the nut, is adapted to the opening e corresponding in shape to the nut and the portion a' . Thus the liability of the parts becoming detached is entirely avoided.

In some instances the head of the nut may be shaped to continue the spherical line of the ball as shown in Fig. 7.

In Figs. 5 and 6, I have shown the cap secured to the shell by a bayonet joint, and when the cap is in position the two parts are locked together by a bolt or pin.

In Figs. 7 and 8, I have shown the shell or socket formed of two halves secured together by bolts. In this instance, the cap forms part of the shell.

Fig. 9, illustrates a method of using rods with balls at each end. In this instance the flight or joint has a double socket.

While I prefer to make each joint a flight of the conveyer, in some instances some of

the flights may be omitted where very few flights are required in the length of the conveyer.

It will be seen that by this construction, a conveyer can be made very cheaply, and in the strongest possible manner, as the links used are simply headed bars, and when it is required to renew the joints, the parts of the socket or the ball itself, can be replaced with very little expense, and the parts can be kept in stock, and flights of different shapes can be attached as required.

I prefer to rigidly secure the several rods to their casings, so that the flights forming part of the casing or attached thereto, will be drawn in line owing to the leverage, as the joint of the link is at the extreme end of the rod; differing in this particular from the ordinary link conveyer and wire rope conveyer.

20 I claim as my invention—

1. In a conveyer, the combination of a series of rods connected together by flights flexibly jointed to said rods, substantially as described.

25 2. In a conveyer, the combination of a series of rods and flights, with ball and socket connection between each rod and one of the flights, substantially as described.

3. In a conveyer, the combination of the flights with a series of rods each having a ball at one end and a socket casing at the other end, the ball of each rod of the series being adapted to the socket casing of the adjoining rod, substantially as described.

35 4. The combination in a conveyer, of a flight, a socket therein, a rod rigidly secured to said flight, and a ball adapted to the socket, and to which is secured another rod, substantially as described.

40 5. The combination in a conveyer, of a series of sockets, a series of rods rigidly attached to the said sockets, and a series of balls at-

tached to the opposite ends of said rods and mounted in the socket casing, substantially as described.

45 6. The combination of the series of balls and socket casings, the rods connecting the same and flights secured to said socket casings, substantially as described.

7. The combination of the rods A, a shell 50 in which the head of the rod is mounted and prevented from turning, with a ball E adapted to said shell, and in which the end of a rod is mounted and prevented from turning in said ball, substantially as described.

55 8. The combination of a rod having at one end a head and portion a, and at the opposite a portion a' and screw threaded portion a³, with a ball adapted to the portion a', and a nut adapted to the threaded portion and also 60 adapted to the ball, a socket having an opening in which the head of the rod is mounted, substantially as described.

65 9. The combination of the rod, a casing D secured to one end of said rod, a ball E secured to the opposite end of the rod, a cap for said casing in which the ball of the adjoining rod is adapted, with means for securing the cap to the casing, substantially as described.

70 10. The combination of the rod, a casing D adapted to one end of said rod, a ball E adapted to the opposite end of the rod, a cap for said casing, with a flight clamped between the cap and casing, and means for clamping the cap 75 to the casing and flight, substantially as described.

In testimony whereof I have signed my name to this specification in the presence of two subscribing witnesses.

JAMES M. DODGE.
